UNITED STATES PATENT OFFICE

153,834

DESIGN FOR A WALL PLAQUE

David D. Stockdale, Ravenna, Ohio

Application May 2, 1947, Serial No. 138,759

Term of patent 3½ years

(Cl. D29—23)

To all whom it may concern:

Be it known that I, David D. Stockdale, a citizen of the United States and resident of Ravenna, Portage County, Ohio, have invented a new, original, and ornamental Design for Wall Plaque, of which the following is a specification, reference being had to the accompanying drawing, forming a part thereof.

In the drawing

Fig. 1 is a front elevational view of my ornamental wall plaque; and

Fig. 2 is a side elevational view thereof.

I claim:

The ornamental design for a wall plaque, as shown.

DAVID D. STOCKDALE.
